1 Claim. (Cl. 176—37)

The present invention relates to a method of relieving the pressure in gas containers and a means for carrying out the method.

The problem which arises when relieving the pressure in gas containers will be dealt with more in detail for a case chosen as an example, namely when the gas container is a component in a gas circulation circuit in a homogeneous boiling reactor, whereby it contains strongly radioactive fission gases. If a fault should occur in the reactor operation, the pressure in the gas container could exceed that permitted and it has therefore been proposed to place the gas container in communication with a gas tank serving as collecting vessel for the gas and having a displaceable lid, in order when necessary to be able to relieve the pressure in the gas container. The method of using such a gas tank for pressure relief is, however, impaired by serious drawbacks since it is extremely difficult to effect a reliable sealing between the displaceable lid and the gas tank itself, so that the risk of leakage from the gas container of strongly radioactive substances is present.

Another way of arranging pressure relief in the gas container is to place it in communication with one or several very large closed collecting vessels freely communicating with each other and having no movable parts. The use of such large vessels, however, also involves disadvantages, partly because it is unfavourable to use large vessels since they require a considerable amount of space and partly because it is difficult to manufacture very large vessels and leak-test them.

By means of the present invention the mentioned drawbacks are avoided in the described collecting vessels and it is possible to use completely closed collecting vessels without movable parts and sealing means and which require considerably less space than the above mentioned large closed collecting vessels.

The invention relates to a method of relieving the pressure in gas containers containing a gas under pressure, for example a gas container containing collected radioactive fission gas formed during operation in a homogeneous reactor, whereby the main part of the gas is transferred to collecting vessels for the gas, connected to the gas container. The invention is characterized in that the gas container with openable and closable connection conduits is connected to several collecting vessels, and that the gas container is placed in open communication with one collecting vessel at a time and the open communication between the gas container and one collecting vessel is closed after the pressure in the gas container and the collecting vessel has become substantially equal, before the gas container is placed in open communication with another collecting vessel. If the collecting vessel with which the gas container is last placed in open communication is evacuated to a pressure below atmospheric pressure before the open communication is established, the particular advantage is attained that the pressure in the gas container may be reduced to below atmospheric pressure so that leakage is prevented from this to the surroundings through a possibly arising crack, which might be the cause of the pres-

2

sure relief being made. To carry out the method it is suitable to use a means in which the collecting vessels are arranged along a main conduit connected to the gas container and the collecting vessels are connected to the main conduit by means of connection conduits containing openable and closable valves, but the collecting vessels could also, via connection conduits having such valves, be directly connected to the gas container without an intermediate main conduit. It is particularly advantageous if the valves in the different connection conduits consist of automatically controlled valves having successively falling opening pressure and successively falling closing pressure.

The invention will be further explained by describing one embodiment with reference to the accompanying figure which shows a schematical picture of a homogeneous boiling reactor with pertaining gas circulation circuit.

The boiling reactor core 2 of the reactor vessel 1, which core contains light or heavy water as moderator, in the device according to the figure, gives off aqueous steam which via the conduit 3 rises into the condenser 4. Apart from the mentioned moderator, the reactor core 2 may for example consist of thorium oxide dispersed in the moderator, and enriched material uranium 233 or uranium 235. The steam is condensed in the condenser and gives off its heat content to the feeding water supplied at 5 and led off at 6. The condensate is returned to the reactor core via the conduit 7. The homogeneous boiling reactor also gives off oxyhydrogen gas because of the radiolytic splitting of the moderator. The oxyhydrogen gas is recombined in the recombiner 8. The conduit between the condenser 4 and the recombiner has been designated 9. Possibly remaining steam from the condenser 4, together with aqueous steam formed in the recombiner and possibly remaining oxyhydrogen, is led via the conduit 10 to a tail condenser 11 which is suitably supplied with feeding water on the secondary side at 12. This water may also be utilized for cooling the condenser 4, whereby it enters the secondary side of the condenser 4 via the conduit 5 as feeding water. Condensate formed in the tail condenser is returned to the reactor core via the conduit 13. The shown system for external recombination of the oxyhydrogen gas, consisting essentially of the recombiner 8 and the tail condenser 11, is unnecessary if internal recombination can be effected, for example by the addition of catalysts to the reactor fuel.

The steam rising from the reactor core is supplied via the conduit 14 with permanent gas, for example hydrogen, deuterium, oxygen, helium, whereby the choice of gas is influenced by the chemical composition of the reactor core. The permanent gas, which comes from the gas container 15, is thus mixed with the steam and is returned to the container 15 when it has passed the condenser 4 and the possibly connected arrangements 8 and 11, via the conduit 16. The circulation of the permanent gas in this closed system is carried out by the gas pump 17. The reason for the introduction of permanent gas into the system is to avoid the fission gas reaching a noxious concentration in the reactor core. Due to the presence of the permanent gas, fission gases formed distribute themselves in a favourable way between the liquid phase in the reactor core and the gas phase. Large amounts of radioactive gas under pressure are collected in the container 15 during the reactor operation. In accordance with the invention the gas container 15 is via a main conduit 18 placed in communication with a number, in the shown case seven, of collecting vessels, in the Figure designated 19a-g. The vessels 19a-f may suitably have atmospheric pressure while the vessel 19g may suitably be evacuated to a pressure below atmospheric pressure. In each conduit 20a-g between the main conduit 18 and

respective collecting vessels 19a-g, an opening valve 21a-g is arranged, and in series with this a closing valve 22a-g. If the pressure in the container 15 exceeds that permitted, for example due to incomplete condensation in the condenser 4, or if a leakage occurs in the gas system, the container 15 is relieved of pressure by the utilization of the collecting vessels 19a-g. Thereby the valve 21a is first opened, which as the rest of the opening valves 21b-g is closed from the beginning. This causes a pressure equalization to take place between the container 15 and the collecting vessel 19a. When the pressure in the vessel 19a approaches or has become the same as that in the container 15, the closing valve 22a is closed, which as the other closing valves 22b-g, is open from the beginning, after which the opening valve 21b is opened. Thus part of the gas in the container 15 is transferred to the vessel 19b. When the pressure in the vessel 19b approaches the reduced pressure in the container 15, the closing valve 22b is closed, and the opening valve 21c is then opened. The same procedure is repeated for the vessel 19c and the other vessels 19d-g, until the main part of the gas quantity in the container 15 has been distributed in the collecting vessels 19a-g. If at the outset the vessel 19g has lower pressure than atmospheric pressure, the final pressure in the gas container 15 may be reduced below atmospheric pressure, which is an advantage if the reason for the pressure relief is a leakage arising in the container 15 or in the gas circulation circuit of the reactor. The opening and closing of each valve may with advantage take place automatically and is then suitably controlled in a known way by means of pressure sensing means in the gas container and respective collecting vessels. Each connection conduit 20a-g need not in accordance with the figure contain two valves, one opening and one closing valve, but these could be replaced by a single valve which is then used both when opening and when closing the respective connection conduits.

The actual operation conditions and dimensioning of the means shown in the figure will be given in the following. At the start of the pressure relief in the container 15 the pressure and temperature in the reactor part are presumed to be 70 atmospheres and 280° C. The total quantity of gas in the system is presumed to be 36 m³, 6 m³ being in the container 15. The collecting vessels 19a-g are double sheathed and are provided with cooling means between the sheaths. All collecting vessels are cylindrical and 6 m. high. The diameter of the vessel 19a is 1.6 m., of the vessel 19b 2 m., of the vessels 19c and 19d 2.5 m., and of the vessels 19e, 19f and 19g 3 m. If it is assumed that the temperature does not alter during the pressure relief and that the pressure in

all the collecting vessels is to start with 1 atmosphere, with the exception of the vessel 19g where the pressure is some mm. Hg, by using the general equation for ideal gases, the pressure in the different collecting vessels after completed pressure relief may easily be calculated to 53 atmospheres for the vessel 19a, 34.5 atmospheres for the vessel 19b, 19 atmospheres for the vessel 19c, 10.5 atmospheres for the vessel 19d, 4.8 atmospheres for the vessel 19e, 2.2 atmospheres for the vessel 19f and 1 atmosphere for the vessel 19g. The total volume in the vessels 19a-g, which relieve the gas container 15 so that the pressure in it becomes 1 atmosphere, is 217 m³. In order to obtain the same pressure relief in the container 15 with a single evacuated collecting vessel or several evacuated collecting vessels communicating with each other, a volume of 2520 m³ would be required.

Although the invention is described particularly for the case where the pressure relief is carried out from a container containing radioactive gases from a homogeneous reactor, it is obvious that it may also be used on other occasions when it is necessary to relieve the pressure in a gas container.

I claim:

Method of relieving pressure in a gas container containing a mass of gas under pressure which comprises connecting the gas container successively to each of a plurality of gas collecting vessels while maintaining it out of communication with any other of the vessels, and maintaining the connection each time until the pressure in the collecting vessel with which the container is connected reaches substantial equilibrium with the pressure of the gas in the container, said gas container being connected to a homogeneous nuclear reactor and containing collected radioactive fission gas formed during operation of the homogeneous reactor, and the last collecting vessel with which the gas container is connected being evacuated to sub-atmospheric pressure before the connection is made.
